RACK FOR DISPLAYING AND DISPENSING SMALL ARTICLES

Joseph Di Domenico and Frank Mellion, Providence, R.I., assignors to Jo-Dee-Corp., Providence, R.I., a corporation of Rhode Island

Filed Apr. 8, 1963, Ser. No. 74,322

Term of patent 14 years

(Cl. D80--9)

FIG. 1

FIG. 2

FIG. 3

FIG. 5

FIG. 1 is a front elevational view of a rack for displaying and dispensing small articles showing our new design, the rear being substantially flat and plain;

FIG. 2 is a bottom edge view thereof;

FIG. 3 is a top edge view thereof;

FIG. 4 is a side elevational view looking from the left with respect to FIG. 1; and

FIG. 5 is a side elevational view looking from the right with respect to FIG. 1.

We claim:

The ornamental design for a rack for displaying and dispensing small articles, substantially as shown and described.
